WILLIAM F. BROWN, OF NEWARK, NEW JERSEY, ASSIGNOR TO THE

DESIGN FOR A CARPET.

SPECIFICATION forming part of Design No. 21,994, dated November 15, 1892.

Application filed October 11, 1892. Serial No. 448,583. Term of patent 8½ years.

To all whom it may concern:

Be it known that I, WILLIAM F. BROWN, a subject of the Queen of Great Britain, residing at Newark, in the county of Essex and State of New Jersey, have invented and produced a new and original Design for Carpets and Similar Fabrics, of which the following is a specification, reference being had to the accompanying fac-simile, forming a portion of the specification, which illustrates a face view of a carpet illustrating my new design.

The invention relates to a design to be worked into or upon surfaces such as carpets and similar fabrics; and it consists in the novel configuration and grouping of the figures herein specifically shown and claimed.

The design consists of a body A and a border B. The body A consists of floral figures arranged in groupings of a festoon order and simulating flowers of the rose, pink, and daisy

type, together with buds, stems, and leaves. The border B has an inner ornamental margin of an arched configuration, a main portion composed of festoons of floral figures in harmony with the body, and an outer margin 25 embracing bar, scallop, and arched figures of a composite type.

I claim—

1. In a design for carpets, the body A, substantially as shown. 30
2. In a design for carpets, the border B, substantially as shown.
3. The design for carpets, consisting of the body A and the border B, substantially as described.

WILLIAM F. BROWN.
